CASING FOR A CALCULATOR OR THE LIKE

Salvatore Jack Magri, Los Altos, Calif., assignor to Litton Business Systems, Inc., Orange, N.J., a corporation of New York

Filed Sept. 19, 1967, Ser. No. 8,658

Term of patent 14 years

(Cl. D64—11)

FIG. 2

FIG. 3

FIG. 4

FIG. 5

FIG. 6

FIG. 1 is a left side perspective view of a casing for a calculator or the like embodying my new design.

FIG. 2 is a left side elevational view thereof.

FIG. 3 is a top plan view.

FIG. 4 is a right side elevational view.

FIG. 5 is a front elevational view; and

FIG. 6 is a rear elevational view.

The broken line disclosure of the calculator keys are shown for illustrative purposes only to show the environment in which the cover case is used.

I claim:

The ornamental design for a casing for a calculator or the like, as shown and described.
